UNITED STATES PATENT OFFICE

2,453,238

BLADE CONTAINER

Edwin A. Locke, Jr., Quincy, Mass., assignor, by
mesne assignments, to Gillette Safety Razor
Company, Boston, Mass., a corporation of Dela-
ware

Application January 8, 1945, Serial No. 571,761

4 Claims. (Cl. 206—16)

1

This invention relates to containers and more particularly to containers which may act not only as a shipping package but also as a convenient dispenser. While my container is not limited to razor blades, it is particularly adapted for use therewith and accordingly for the purpose of disclosing my invention, I have shown and will describe its use in connection with razor blades.

A further object of the invention is not only to provide a package which may hold new blades but also a package having a suitable compartment for used blades so that they may be disposed of without danger to the fingers. I have accordingly prepared a single unit which acts not only as a merchandising package but also as a dispensing and disposition unit.

Other objects and advantages of my invention will become apparent as the description proceeds.

In the accompanying drawing:

Figure 1 is a perspective view showing a container embodying my invention.

Figure 2 is a cross-sectional view of the container taken along the lines 2—2 of Figure 3.

Figure 3 is a cross-sectional view taken along the lines 3—3 of Figure 2.

Figure 4 is a cross sectional view taken along the lines 4—4 of Figure 2.

Figure 5 is a perspective view of resilient member forming a part of the package.

Figure 6 is a perspective view of the portion of the package which forms the used blade compartment.

Figures 7 and 8 are views of the planks from which the carton is assembled.

Referring particularly to the drawings, the container 10, is made of three members, the outer enclosure or covering 11, shown in Figure 7 in the form of a flat blank which forms bottom, top and sides of the container, the used blade compartment 12, and the resilient member 14. The outer container 11, consists of side members 21 and 22 with connecting flaps 23 and 24 combining to form one end in which is defined a circular opening 25. The other end of the container is formed by the intermediate connecting section 26 in which a suitable opening 27, is formed. The flap 28, connected to one side of the member 21, forms the bottom of the container while the flap 29, forms the top thereof.

A slot, 30, is provided in the flap 29 to form an entrance into the used blade compartment. One edge of the flap 29, is also cut away slightly at 31, the purpose of which will be disclosed later. Connecting tab 32 is attached to the cover member 29, so that the box may be closed and connecting

2

tabs 33, 34 and 35 are provided so that the box may be pasted or glued together. An assembled blank 11, forms the outside container as shown in Figure 1 with the flap 23 engaging the end 24, tabs 34 and 35 being folded under the bottom 28 and the tab 33 engaging the inner portion of the side 22 in the customary manner.

The blank 12 for the used blade compartment, consists of tab 40, ends 41 and 42 and sides 43 and 44. The side 44 is considerably longer than the side 43 so that when the blank 12 is folded into position and the tab 40 glued or otherwise secured to the side 44, an extension 45, as particularly shown in Figure 6, will extend beyond the end 41, of this member. This extension 45 positions the used blade compartment when the whole container is assembled so that the used blade compartment is free to move to some degree within the outer container formed by the blank 11. A resilient member is formed from card board or other suitable material, bent upon itself without scoring and joined at 50. The sides, 51 and 52, are bent inwardly along offset lines 53 and 54 while the other two sides 55 and 56, are parallel. Member 14 may be compressed by pressing the sides, 55 and 56, toward each other but will have sufficient resilience to urge these sides away from each other.

Merchandise such as razor blades 60, is packed between the end 26, and the resilient member 14, which is in turn pushed against the end 41, of the used blade compartment 12. The blades may be placed against the end 26, so that the trademark will appear through the opening 27, and it will be possible to ascertain whether any blades are still in the container. The cut away portion 31, forms with the end 26 an exit slot 57, through which the blades may be moved by the use of the thumb inserted in the opening 27. As the blades are used the resilient member 14, will have a tendency to push the unused blades toward the end 26 of the box, keeping the outermost blade always in line with the delivery slot.

In examining Figure 3, it will be seen that the extension, 45, terminates somewhat short of the end, 26, of the container. It will be noted that there is an opening, 25, in the end, 24, of the container as is clearly shown in Figure 3. When the supply of blades is depleted it is possible to supplement the action of the resilient member 14, by exerting pressure on the used blade compartment 12, through the opening 25. This may be moved toward the end 26, until the extension 45 abuts the end 26 of the container.

It will be seen that I have disclosed a rela-

tively inexpensive combined blade package and dispenser with means for disposing of used blades all in one unit. When all of the blades have been used the entire package may be thrown away without the necessity of disposing of loose used blades or if desired, it may be emptied and new blades inserted, and reused.

It will be appreciated that while I have disclosed my invention as applied to a blade holder or container, that its use is not so limited but that it may be adapted for a number of other uses.

I claim—

1. A container for razor blades or the like, comprising an elongated enclosure having side walls, ends, bottom, and a cover having an outlet slot adjacent one end thereof, the said end having an opening therein, a stack of blades within the enclosure adjacent the said end, a compartment for used blades disposed within the enclosure adjacent to the other end of the container, the cover of the enclosure having a slot communicating with said compartment, and a resilient member disposed between said compartment and the blade stack and serving to hold the outermost blade of the stack always in alignment with the outlet slot in all positions of the container, the other end of the enclosure having a hole through which the compartment for used blades may be engaged and pushed inwardly with said resilient member against the blade stack.

2. A container for razor blades and the like, comprising an outer enclosure having sides, ends, and a cover, each of said ends being apertured, a compartment slidably contained within the enclosure, the cover of the enclosure having a slot communicating with said compartment in all positions thereof and a delivery slot at one end, a plurality of blades positioned beneath the slotted end of said cover adjacent to the end of the enclosure, spring means for so positioning said

blades, the said compartment being shorter than the said enclosure and slidable therein and having an extension limiting said sliding movement.

3. A dispensing container for razor blades, comprising walls forming a rectangular enclosure, a cover for the enclosure having a delivery slot at one end, the enclosure having end walls both provided with openings, a used blade receptacle movable within the enclosure, a spring backed by said receptacle, a stack of blades held by said spring with the outermost blade against one end of the enclosure, the opening in the other end of the enclosure affording access whereby the used blade receptacle may be moved within the enclosure.

4. A dispensing container for blades, comprising a closed rectangular box having end walls each provided with an aperture, and a cover providing an outlet slot at one end of the box and an inlet slot at an intermediate location, a used blade receptacle movably contained within the box, a spring bearing against one end of said receptacle, and a stack of blades held under pressure between said spring and one end of the box whereby the outermost blade may be aligned with the outlet slot, the aperture in the other end wall providing access to said receptacle through which it may be moved to effect the same purpose.
